UNITED STATES PATENT OFFICE.

JOHN VAN BRUNT, OF FLUSHING, NEW YORK, ASSIGNOR TO COMBUSTION ENGINEERING CORPORATION, OF NEW YORK, N. Y., A CORPORATION OF NEW YORK.

VALVE.

1,416,391.

Specification of Letters Patent. Patented May 16, 1922.

Application filed July 23, 1920. Serial No. 398,400.

To all whom it may concern:

Be it known that I, JOHN VAN BRUNT, a citizen of the United States, residing at Flushing, county of Queens and State of New York, have invented a certain new and useful Improvement in Valves, of which the following is a full, clear, and exact description.

My invention relates to improvements in valves, being particularly adapted to a balanced or lifting type of throttle valve which is very well known in the trade and is frequently used in conjunction with steam pressure regulators of the hydraulic type in which a slight variation of steam pressure will cause a definite movement of the piston through hydraulic means. These valves are ordinarily actuated through levers having fixed fulcrums, the levers being in turn actuated by hydraulic regulators controlled by variations in steam pressure. In the usual form of hydraulic regulator the piston has a maximum stroke or travel of about ten inches and for a fall in pressure of approximately one and one-half or two pounds will travel the full ten inches and for fractional parts of such variation in pressure will travel a corresponding fraction of its full stroke, moving the valve lever corresponding amounts.

An objection is found to this type of valve in this class of work in that the size of the valve or port openings of the valve, as commercially manufactured, is usually not proportioned to the amount of steam required for the maximum flow and the valve is not properly adjustable. For instance, if the valve is regulating an engine which is driving a forced draught fan, it will be found that the usual valve will pass very much more steam in its maximum or intermediate openings than is necessary, so that frequently an engine or turbine will go from its minimum speed to the maximum speed with a movement of only one-quarter or one-fifth, or even less, of the maximum possible travel of the valve. The result is that the fan engine will alternately be running at its maximum speed and at its minimum speed and at no time will the actual air supplied be proportioned to the demand for steam.

The object of my invention is to do away with these objections and to provide a valve which can be adjusted through its actuating

lever so that the maximum port opening for a full movement of the regulator piston will be just sufficient to drive the engine or turbine at its maximum speed. On account of varying conditions in different plants it is very difficult to proportion a valve to such requirements in advance and a valve in which the maximum port opening can be adjusted after installation to meet the conditions present has a very definite value.

The following is a description of an embodiment of my invention, reference being had to the accompanying drawings, in which,

Fig. 1 shows an embodiment of my invention in connection with a balanced throttle valve, the valve-casing being in section;

Fig. 2 shows an end elevation of the same partially in section on the line 2-2;

Fig. 3 is an end elevation of the lever supporting and guiding member looking toward the right-hand end of Fig. 1;

Fig. 4 is a detail plan view of the parts shown in Fig. 3 with the lever, valve-stem and fulcrum link omitted; and,

Fig. 5 is a detail showing the lever, fulcrum link, block and support therefor looking toward the left-hand end of Fig. 1.

Referring more particularly to the drawings, 1 is the valve-casing of a throttle valve having a balanced plunger 2 passing through valve-seats 3-3 therein and functioning in the manner well understood, these parts being a well known construction. 4 is the valve-stem connected to the valve 2 and extending through the projection 5 on the cover 6 of the valve-casing. 7 is a support having an extension 8 in the form of a hollow cylinder surrounding the projection 5 and secured in place by a nut 9 screwed thereon. 10 This support 7 is provided with a surface 10 and a series of holes 11, both of which are parallel to the axis of a lever 12 connected to the valve-stem at 13 and fulcrumed at 14 when the lever is in the position corresponding to the closed position of the valve 2. The surface 10 and series of holes 11 are preferably inclined as in Fig. 1. The fulcrum 14 is provided by a fulcrum link 15 carrying the fulcrum 14, which is adapted to be introduced to any one of a series of holes 16 in line with the axis of the lever 12. The lower end of the fulcrum link 15 is pivoted at 17 to a block 18, which rests upon the surface 10 and can be adjusted along that

surface, being held in any desired adjusted position by the bolt 19 passing through one of the series of perforations 11. The link 15 is preferably substantially parallel to the 5 valve-stem 4 and can be adjusted toward or from that valve-stem by changing the positions of the bolts 14 and 19. The surface 10 being parallel to the axis of the lever 12 when the valve is in closed position, the link 10 15 can be adjusted toward and from the valve-stem 4 when the valve is closed without changing the position of the lever 12. Two important results of this arrangement are that when the link 15 is adjusted nearer to 15 the valve-stem 4 the valve will begin to open substantially as quickly as it would before adjustment, but on account of the shortening of the load-arm by such adjustment the full throw of the lever 12 will not open the valve 20 2 to as great an extent as before adjustment. The lever 12 in its full movement preferably moves from one side to the other of a horizontal plane passing through its fulcrum.

In a corresponding manner, when the link 15 25 is moved away from the valve-stem 4 the time of opening of the valve 2 will not be modified but the maximum opening of that valve for a full throw of the lever 12 will be increased. The valve therefore can be very easily ad- 30 justed after installation so as to vary the maximum port opening in either direction to the desired extent without affecting the time of the initial opening of the valve. In the position shown, the valve is closed, the top of 35 the valve ports 20 therein being in line with the top of the valve seats 3, the downward throw of the valve being limited by the stops 21, and any upward movement of the valve 2 from the position shown in Fig. 1 results in 40 an immediate partial opening of the valve.

If the fulcrum 14 is moved to the left by using the left-hand holes of the series 16 and 11, the maximum lift of the valve for a full movement of the lever will be cor- 45 respondingly increased and the steam passed will be proportional to the parts of the open- 50 ings 20 which are above the valve seats. If with this adjustment those openings are too large for a given movement of the lever 55 they may be reduced by moving the fulcrum in toward the valve-stem. If the fulcrum be adjusted by using the innermost holes of the series 16 and 11 the maximum lift of the valve 2 for the maximum travel of the outer 60 end of the lever will be reduced in propor- 65 tion as the load arm is reduced. In this way it is possible to closely control the extent of opening of the valve for a given movement of the lever. The device may be applied to 60 existing valves of the general type of balanced throttle valve now in use. The power- 65 arm of the lever is guided in a slot formed by the base 22 and plate 23 secured thereto. A semi-circular flange 24 is secured to the sup- 65 port 7 and cylinder 8 so as to afford a sup-

porting base for those parts. From this base there also rises an arm 25 carrying a guide 26 for the upper end of the valve-stem 4. 27 is an ordinary stuffing box.

As will be evident to those skilled in the art, my invention permits of various modifications without departing from the spirit thereof or the scope of the appended claims.

What I claim is:

1. The combination of a valve-casing, a valve reciprocating therein and a valve-stem extending through and guided for movement in a straight line by the casing, with a lever pivotally connected to said valve-stem, the axes of the pivotal connection being fixed relatively to said lever, a fulcrum for the lever, and means for adjusting said fulcrum toward and from said valve-stem along said lever when said valve is in closed position without changing the 85 position of said lever.

2. The combination of a valve-casing, a balanced plunger valve reciprocating therein and a valve-stem extending through and guided for movement in a straight line by the casing, with a lever pivotally connected to said valve-stem the axis of the pivotal connection being fixed relatively to said lever, a fulcrum for the lever, a support for said fulcrum, and means for adjusting 90 said fulcrum upon said support toward and from said valve-stem along the axis of said lever when said valve is in closed position without changing the position of said lever.

3. The combination of a valve-casing, a valve reciprocating therein and a valve-stem extending through and guided for movement in a straight line by the casing, with a lever connected to said valve-stem, an adjustable fulcrum link for said lever, 105 a fixed abutment for supporting the lower end of said link, and means for adjusting both ends of said link toward and from said valve-stem when said valve is in closed position, without changing the position of said 110 lever.

4. The combination of a valve-casing, a valve reciprocating therein and a valve-stem projecting therefrom, with a lever connected to said valve-stem, an adjustable fulcrum link therefor, a block to which the lower end of said link is pivoted, a support for said block, and means for adjusting said block along said support and the upper end of said link along said lever toward and 115 from said valve-stem in substantially parallel lines when said valve is closed.

5. The combination of a valve-casing, a valve reciprocating therein and a valve-stem projecting therefrom, with a lever connected to said valve-stem, an adjustable fulcrum link therefor, a block to which the lower end of said link is pivoted, a support for said block, and means for adjusting said block along said support and the upper end 120 125 130

of said link along said lever toward and from said valve-stem in substantially parallel lines when said valve is closed, one of said parallel lines constituting the axis of 5 said lever.

6. The combination of a valve-casing, a valve reciprocating therein and a valve-stem projecting therefrom, with a lever connected to said valve-stem, an adjustable fulcrum 10 link for said lever, an abutment for supporting the lower end of said link, means for adjusting both ends of said link along lines substantially parallel to the axis of said lever when said valve is in closed position 15 without changing the position of said lever, said valve-casing having a projection surrounding said valve-stem and said abutment having an extension surrounding said pro-

jection, and a nut upon said projection securing said abutment to said valve-casing. 20

7. The combination of a valve and means for opening and closing the valve comprising a valve stem, a lever operatively connected with the valve stem between the ends of the lever, a fixed support, and a link having 25 one end pivoted on the support and its other end pivotally connected with the lever to serve as a fulcrum about which the lever is turned in operating the valve, said lever, link and support having provision to enable 30 both ends of the link to be adjusted toward and from the valve stem without varying the position of the lever when the valve is in one position.

JOHN VAN BRUNT.
